(57) **CLAIM**

The ornamental design for a single battery pack inverter, as shown and described.

DESCRIPTION

FIG. 1 is a front perspective view of a single battery pack inverter according to one construction.

FIG. 2 is a front view of the single battery pack inverter as shown in FIG. 1.

FIG. 3 is a rear view of the single battery pack inverter as shown in FIG. 1.

FIG. 4 is a first side view of the single battery pack inverter as shown in FIG. 1.

FIG. 5 is a second side view of the single battery pack inverter as shown in FIG. 1.

FIG. 6 is a top view of the single battery pack inverter as shown in FIG. 1; and,

FIG. 7 is a bottom view of the single battery pack inverter as shown in FIG. 1.

Portions of the portable power source shown in broken lines are included for the purpose of illustrating environment and form no part of the claimed design.
